(57) **CLAIM**

We claim the ornamental design for a light emitting sculpture, as shown and described.

DESCRIPTION

FIG. 1 is a perspective view of the light emitting sculpture;
FIG. 2 is a front view thereof;

FIG. 3 is a first side view thereof, the second side being a mirror image thereof;

FIG. 4 is a rear view therof;

FIG. 5 is a top view thereof; and,

FIG. 6 is a bottom view thereof.

The broken line disclosure of portions of the article is for illustrative purposes only and forms no part of the claimed design.
